AUTOMATIC WASHER AND EXTRACTOR DRIER

Clarence V. Bells, Redmond, Oreg.

Application December 28, 1953, Serial No. 400,619

4 Claims. (Cl. 68—25)

This invention relates in general to improvements in washing machines for clothing and similar articles, and more specifically to an improved automatic washer and extractor drier.

The primary object of this invention is to provide an improved washing machine which includes convenient receptacles for receiving clothing or like articles whereby such clothing may be rotated through a cleaning liquid, the washing machine being so constructed whereby when the cleaning liquid is removed, the clothing may be revolved at a relatively great rate so as to cause centrifugal extraction of the cleaning liquid from the clothing.

Another object of this invention is to provide an improved automatic washer and extractor drier which includes a clothing receptacle supported within a container for cleaning fluid, there being provided novel drive means for selectively rotating and revolving the receptacle whereby clothing carried thereby may be selectively washed or dried.

A further object of this invention is to provide an improved washing machine which includes a clothing receptacle rotatably mounted within a container and having drive means for selectively revolving the same, the drive means having associated therewith manual controllable means whereby clothing receiving openings in both the container and the receptacle may be selectively aligned to permit the insertion or removal of clothing.

A still further object of this invention is to provide an automatic washer and extractor drier which includes a housing having a portion thereof forming a cleaning fluid container in which clothes may be selectively rotated to effect cleaning thereof, a portion of the housing also forming fluid receptacles whereby cleaning fluids and rinse fluids may be selectively stored between periods of utilization.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is top plan view of the automatic washer and extractor drier which is the subject of this invention and shows the general outline thereof;

Figure 2 is a side elevational view of the automatic washer and extractor drier of Figure 1;

Figure 3 is an enlarged vertical sectional view taken substantially upon the plane indicated by the section line 3—3 of Figure 1 and shows the general relationship of clothing receptacles with respect to the main housing of the washer and the drive means for selectively rotating and revolving the clothes receptacles;

Figure 4 is a transverse horizontal sectional view on a reduced scale, taken substantially upon the plane indicated by the section line 4—4 of Figure 3 and shows the relationship of fluid receptacles in the bottom of the housing and means for returning fluid disposed therein

2

into the main container of the housing, the view being on a small scale;

Figure 5 is a vertical sectional view on a reduced scale, taken substantially upon the plane indicated by the section line 5—5 of Figure 3 and shows the relationship of the various portions of the washer;

Figure 6 is an enlarged fragmentary horizontal sectional view taken substantially upon the plane indicated by the section line 6—6 of Figure 3 and shows a portion 10 of the general construction of one of the couplings; and

Figure 7 is an enlarged fragmentary vertical sectional view through a portion of a gear housing mounted on the top of the main housing and shows the relationship of a shift rod and electro-magnetic means for operating the same, also being shown is the manner in which an auxiliary manually controlled drive shaft is mounted.

Referring now to the drawings in detail, it will be seen that there is illustrated the automatic washer and extractor drier which is the subject of this invention.

20 The automatic washer and extractor drier includes a main housing which is referred to in general by the reference numeral 10. The main housing 10 is generally cylindrical in outline and is circular in horizontal cross-section. The housing 10 includes a cylindrical vertical wall portion 12, a horizontal top wall 14 and a horizontal bottom wall 16.

The housing 10 includes a substantially horizontal partition 18 which is disposed intermediate the top wall 14 and the bottom wall 16. The horizontal partition 30 divides the housing 10 into an upper container 20 and a lower fluid receiving area. The lower fluid receiving area is sub-divided into a fluid receptacle 22 and a fluid receptacle 24 by a vertical partition 26.

Carried by the horizontal partition 18 is an upstanding support 28. The support 28 has mounted in its upper end a bearing 32 in which is received and supported a lower end of a vertical shaft 30 for rotation. The vertical shaft 30 has its upper end secured to a gear housing 34. Secured to the upper portion of the gear housing 34 is a tubular shaft 36. The tubular shaft 36 has the upper portion thereof rotatably journaled in a bearing 38 carried by the top wall 14. It will be understood that the bearing 38 is sealed against entrance of water or other cleaning fluid carried by the container 20 by a sealing ring 40.

Rotatably carried by the gear housing 34 and extending out thereof is a horizontal shaft 42. The horizontal shaft 42 has mounted on the outer ends thereof for rotation therewith a pair of clothes receptacles which are 50 referred to in general by the reference numeral 44. Extending vertically through the tubular shaft 36 and rotatably journaled in bearings 46 carried thereby in vertical spaced relation is a vertical drive shaft 48. The vertical drive shaft 48 has mounted on its lower end a gear 50 which is intermeshed with a gear 52 carried by the shaft 42 so that the shaft 42 may be rotated in response to rotation of the drive shaft 48. It will thus be seen that the clothes receptacles 44 may be rotated in response to rotation of the drive shaft 48 and revolved 60 in response to rotation of the tubular shaft 36.

Carried by the top wall 14 of the housing 10 is a power unit 54 which is preferably in the form of an electric motor or any other power units may be utilized. The power unit 54 includes a drive shaft 56 which extends 65 into a gear housing 58 carried by the top wall 14 and is journaled therein as at 60. Carried by the end of the drive shaft 56 disposed within the gear housing 58 is a drive gear 62.

Referring now to Figures 3 and 6 in particular, it will 70 be seen that carried by the upper end of the tubular shaft 36 is a gear 64. The gear 64 includes a collar portion 66 and a lower splined portion 68. The lower splined por-

tion 68 is splined to the interior of the shaft 36 so that the gear 64 may be selectively moved vertically and at the same time be in driving connection with respect to the tubular shaft 36. Thus the gear 64 may be selectively meshed with the gear 62 to effect driving of the tubular shaft 36 by the power unit 54.

Referring once again to Figure 3, it will be seen that the upper part of the gear housing 58 is provided with a bearing 70 in which is rotatably journaled an extreme upper end of the drive shaft 48. Mounted on the upper portion of the drive shaft 48 and splined thereto for vertical movement is a gear 72. The gear 72, like the gear 64 includes a collar portion 74. It will be understood that the gear 72 is selectively engageable with the drive gear 62 to effect driving of the drive shaft 48 by the power unit 54.

In order to effect the selective engagement of the gears 64 and 72 with the gear 62, there is provided a shifting yoke which is referred to in general by the reference numeral 76. The shifting yoke 76 includes a vertical portion 78 and a pair of horizontal leg portions 80 and 82. The horizontal leg portion 80 terminates in a bifurcated free end 84 which has pivotally carried thereby a ring 86 carried by the collar portion 74 for rotation with respect thereto. The lower leg 82 terminates in a similar bifurcated end portion 88, as is best illustrated in Figure 6, and has carried thereby for pivotal movement a ring 90. The ring 90 is rotatably carried by the collar portion 66 of the gear 64.

The proportions of the shifting yoke 76 are such that only one of the gears 64 and 72 may be engaged with the drive gear 62 at one time. It will be seen that when the shifting yoke 76 is in its uppermost position, the gear 64 is engaged with the drive gear 62 and when the shifting yoke 76 is in its lowermost position, the gear 72 is engaged with the drive gear 62. When the shifting yoke 76 is in a central position, neither of the two gears 64 and 72 are engaged with the drive gear 62.

Referring now to Figure 7 in particular, it will be seen that carried by the gear housing 58 on the side thereof remote from the power unit 54 is a small housing 92. The housing 92 has mounted therein an electro-magnetic device 94 of which the vertical portion 78 of the shifting yoke 76 forms a part. The electromagnetic device 94 includes a sleeve portion 96 which is provided with windings and other necessary electrical fittings (not shown) and has passed therethrough the vertical portion 78. The vertical portion 78 is provided in spaced relation on opposite sides of the sleeve portion 96 with collars 98. Mounted on the vertical portion 78 and disposed between their respective collars 98 and the housing 92 are coil springs 100 which serve to normally retain the vertical portion 78 in a neutral position. When the coil of the electro-magnetic device 94 is energized with the current passing in one direction, it will be seen that the vertical portion 78 will be moved vertically and when the current is shut-off the springs 100 will move the vertical portion 78 back to its neutral position. Then when the flow of current is reversed, the vertical portion 78 will be moved downwardly. Thus it will be seen that the electro-magnetic device 94 may be utilized for shifting the shifting yoke 76 and thereby remotely controlling the engagement of the gears 64 and 72 with the drive gear 62.

In the operation of the washer and extractor drier, it will be seen that when the container 20 is filled with a suitable cleaning fluid, such as water and a suitable soap or detergent, the clothes receptacles 44 may be rotated through the driving of the drive shaft 48. After the clothes have been sufficiently washed, the cleaning fluid may then be removed from the container 20. Then the clothes receptacles 44 may be revolved through the driving of the tubular shaft 36. At this time, due to the action of centrifugal forces on the clothes and the liquid or fluid contained therein, the liquid or fluid will be removed from the clothes carried by the clothes receptacles 44. It is

to be understood that the cleaning fluid will enter and pass out of the clothes receptacles 44 through the numerous apertures 102 therein.

In order to effect the placing of clothes and removal of clothes relative to the clothes receptacles 44, the container 20 is provided in the vertical portion 12 with an opening 104 which is selectively closed by a door 106 or other suitable closure. Also, each of the clothes receptacles 44 is provided with a suitable door 105. In order to effect the alignment of the doors 106 with the door 105, there is provided a manually operable drive shaft 108. The drive shaft 108 is rotatably journaled both in a support bracket 110 carried by the top wall 14 and a bearing 112 carried by the gear housing 58, as is best illustrated in Figure 7. The inner end of the drive shaft 108 is provided with a gear 114 which is selectively engageable with the gear 64. The outer end of the drive shaft 108 is provided with a hand wheel 116 through which the drive shaft 108 may be manually turned.

Referring now to Figure 7 in particular, it will be seen that carried by the drive shaft 108 within the confines of the housing 92 through which it passes is a collar 118. The collar 118 has bearing thereagainst one end of a spring 120 whose opposite end bears against the outer surface of the gear housing 58 opposite from the bearing 112. Thus, the drive shaft 108 is normally urged to the left, as viewed in Figure 7. When it is desired to revolve the clothes receptacles 44 to align the doors 105 and 106, the drive shaft 108 is moved inwardly against the outward urging of the spring 120 until the gear 114 intermeshes with the gear 64. Then through the utilization of the hand wheel 116, the clothes receptacles 44 are revolved until the doors 105 and 106 are aligned.

Inasmuch as it is highly undesirable to open the door 105 when the container 20 is filled with a cleaning fluid, the housing 110 is provided with a sight glass 122. The sight glass 122 facilitates the determining of the amount of cleaning fluid remaining within the container 20.

Mounted on the vertical portion 12 of the housing 10 is a pump 124. The pump 124 is provided with an intake line 126 which has a first intake 128 disposed in the fluid receptacle 24. The intake line 126 also passes through the vertical partition 26 and terminates in a second intake 130 which is disposed within the fluid receptacle 22. It is to be understood that the intakes 128 and 130 are provided with separably actuatable, electrically controlled valves (not shown) whereby the fluid may be selectively drawn from either the fluid receptacle 22 or the fluid receptacle 24 by the pump 124. The pump 124 also includes an outlet 132 which is communicated with the interior of the container 20 so that fluids pumped from the fluid receptacles 22 and 24 may be pumped back into the container 20.

Carried by the horizontal partition 18 is an electrically controlled valve 134. The valve 134 permits the selective communication of the container 20 with the fluid receptacle 22 so that fluids carried by the container 20 may be selectively drained into the fluid receptacle 22. A similar electrically controlled valve 136 communicates the container 20 and the fluid receptacle 24.

It is to be understood that the fluid receptacle 22 may receive a cleaning fluid from the container 20 while the fluid receptacle 24 will receive a rinse fluid. In order that water may be saved, it will be seen that the rinse fluids and the cleaning fluids may be utilized over and over. Further, the fluid receptacles 22 and 24 are provided with main lines 138 and 140, respectively, which permit the draining of fluids from the fluid receptacles 22 and 24 to a filter (not shown). There is also provided a return line 142 which may be connected to the filter for returning water from the filter to the container 20. A line 144 is also communicated with the container 20 so that a fresh water supply may be introduced into the system.

It is realized that no specific switch mechanism has

been disclosed for the operation of the various portions of the invention. However, it is readily apparent that inasmuch as each and every step in the operation of the automatic washer and extractor drier is electrically controlled, a suitable switch control mechanism may be provided. If it is desired that the operation of the invention be automatic, a conventional type of timer switch may be utilized for sequentially operating the valves and the electro-magnetic device 94, as well as the power unit 54. On the other hand, in large installations where the machine is provided with an attendant, the various switches may be manually controlled. Inasmuch as the particular switch construction is not a part of this invention, it is not believed necessary to attempt to disclose a switch in more detail.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claims.

What is claimed as new is as follows:

1. A washing machine comprising a fluid compartment, a pair of oppositely disposed receptacles mounted in said compartment for rotation about a mutual horizontal and vertical axis, a rotatable tubular shaft rotatable on a vertical axis journaled in said compartment adjacent said receptacles, a shaft rotatable on a horizontal axis carried by a lower portion of said tubular shaft and rotatable on the vertical axis thereof, the shaft rotatable on a horizontal axis having end portions integrally connected to said receptacles, a shaft rotatably journaled in said tubular shaft and having ends extending beyond the ends of the tubular shaft, angularly related power transfer means connected to the lower end of the shaft rotatable in the tubular shaft and the shaft rotatable on a horizontal axis, a first drive gear including a portion reciprocable in an upper portion of the tubular shaft, said drive gear extending out of said fluid compartment, a second drive gear operably connected to an upper por-

tion of the shaft journaled in the tubular shaft, said last mentioned shaft passing through said first drive gear, a power driven gear rotatable on a horizontal axis between the first and second drive gears for operable engagement therewith, clutch means operably connected to the first and second drive gears for alternately moving one or the other of said drive gears relative to the vertical axis of rotation of the tubular shaft and into engagement with said power driven gear, and means operably connected to said clutch means for urging said drive gears toward a neutral position in opposition to said clutch means.

2. In a washing machine as set forth in claim 1 wherein in a longitudinally adjustable gear means rotatable on a horizontal axis is provided to operably engage said first drive gear for orienting the receptacle contained in said fluid compartment.

3. In a washing machine as set forth in claim 1 wherein in said clutch means includes a pair of parallel fork members each operably engageable with one of said drive gears, said fork members being connected at an end portion by a vertical rod parallel to the vertical axis of rotation of said drive gears, and resilient means on said vertical rods tending to maintain said drive gears out of contact with the power driven gear.

4. In a washing machine as set forth in claim 3 wherein in a longitudinally adjustable gear means rotatable on a horizontal axis is provided to operably engage said first drive gear for orienting the receptacles contained in said fluid compartment.
